UNITED STATES PATENT OFFICE.

ALBERT BROADMEYER, OF HARRISBURG, PENNSYLVANIA, ASSIGNOR TO W. O. HICKOCK MANUFACTURING COMPANY, OF HARRISBURG, PENNSYLVANIA, A CORPORATION OF PENNSYLVANIA.

SHEET RECEIVING AND FEEDING MECHANISM.

Application filed January 12, 1923. Serial No. 612,321.

To all whom it may concern:

Be it known that I, ALBERT BROADMEYER, a citizen of the United States, residing at Harrisburg, in the county of Dauphin and State of Pennsylvania, have invented certain new and useful Improvements in Sheet Receiving and Feeding Mechanisms, of which the following is a specification.

While the present invention is peculiarly useful in connection with ruling machines of the type known as "Dual-L", in which the sheets after being ruled in one direction by one apparatus, are fed to another ruling apparatus arranged at right angles thereto for ruling lines transversely to the first lines ruled, there are features of the invention that are useful in connection with other types of machines.

The object is to provide means for receiving sheets moving in a predetermined direction and starting said sheets in an angular direction, said means being simple and practical and capable of being properly timed, so that each sheet will be removed from the path of the succeeding sheet and there will be no interference or piling up between such sheets.

In the accompanying drawings:

Figure 1 is a plan view of the above described type of ruling machine, and illustrating the sheet-receiving and delivering means,

Figure 2 is a longitudinal sectional view taken substantially on the line 2—2 of Figure 1,

Figure 3 is a sectional view on the line 3—3 of Figure 2,

Figure 4 is a plan view of the receiving and delivering means.

Figures 5 and 6 are detail sectional views, respectively, on the lines 5—5 and 6—6 of Figure 4.

In the accompanying drawings, the first of the two ruling machines is designated generally by the reference numeral 7, and the second machine by the reference numeral 8. These two machines may be of any well known or desired character, and are shown diagrammatically. The sheets

after being ruled in the first machine follow the course of the arrows illustrated in Figure 2 and are delivered by cords indicated at 9 on to a series of spaced angular bars 10 arranged longitudinally in the rear end of the machine. The final position of the sheets on the said bars 10 is determined by a stop plate 11 slidably mounted on said bars 10, and having brackets 12 at their ends, said brackets being slidable on guide bars 13. The adjustment of the stop plate 11 along the supporting bars 10 is effected by sprocket chains or cable members 14 that pass around sprocket wheels 15 located below the end portions of the supporting bars 10, said sprocket chains being connected to the brackets 12. By moving these chains, obviously the plate 11 can be moved to different positions. For the purpose of effecting the movement of the sheets along the supporting bars 10, endless tapes 16 are employed that pass around rollers 17 at the ends of the bars. The rollers 17 at the rear end of the machine are carried by a shaft 18 that is belted, as illustrated at 19 to one of the rollers 20, around which the conveying belt and cords of the machine operate.

Located in the rear end of the machine 7 alongside the supporting bars 10 and adjacent to the juncture of the machine 8 with the machine 7, is a sheet-moving member in the form of a roller 21 that is disposed longitudinally of the direction of movement of the sheets over the bars 10. This roller 21 is continuously driven from the second machine 8 through suitable gearing and belting, illustrated generally at 22 in Figure 1. It is so placed that the margins of the sheets delivered on to the supporting rods 10 will overlie said roller, as indicated at A in Figures 3 and 6. Arranged longitudinally above the roller 21 is a shaft 23 that is provided with one or more gripping cams 24. The peripheral portion of each cam from B to C, as shown in Figure 6, is on the radius of a circle that will cause said portion to coact with the roller 21 and grip the margin of the sheet A against the same. The re-

maining portion of the cam is of considerably less diameter, and as indicated in Figure 6, is thus spaced a considerable distance from the roller 21. The shaft 23 further-
5 more carries at one end a friction wheel 25, the radius of which is such that it will also coact directly with the roller 21, but which has a cut-out portion 26 that leaves a space between said roller 21 and wheel 25 when
10 the cams 24 are out of coaction with the roller 21. This will be clear by a comparison of Figures 5 and 6. The shaft 23 is free to rotate and it is overbalanced by the utilization of weights 27 and 28 carried by the
15 cams 24 and friction wheel 25. Said shaft is, however, normally held against movement, and to this end it is provided with a pin 29 adapted to be engaged by one arm 30 of a stop lever pivoted on the frame of the
20 machine 7, as shown at 31, and having its other end 32 coacting with a cam 33. This cam 33 is mounted on a shaft 34 journaled transversely in the frame of the machine 7, and geared, as shown at 35, in Figure 1, to
25 the driving shaft 36 of the machine.

Means are provided for carrying off the sheets moved by the roller 21 and delivering them to the second machine 8. Thus a roller 37 is illustrated alongside the roller 21 and
30 a second feed roller 38 is shown with friction rollers 39 operating thereon. A suitable conveyer 40 has its receiving end adjacent to the rollers 38 and 39.

Briefly described, the operation of the apparatus is as follows: The sheets successively passing through the machine 7, are ruled in the well-known manner and are successively delivered on to the rods 10, as will be evident. Each is carried along the rods 10 by
35 the tapes 16 until stopped by the plate 11. During this movement, although the roller 21 is in operation, the shaft 23 is stationary with the cams 24 raised. The controlling cam 33 for the stop lever 30-32 is continuously in operation and is timed so that when a sheet is positioned against the stop 11, the stop arm 30 is raised. This movement is occasioned by the arm 32 riding against the flat portion of the cam 33 and a spring 32^a
40 serves to swing the lever and raise the arm 30 out of engagement with the pin 29. As soon as this takes place the shaft 23 is released and the weights 27 and 28 will cause an initial rotation of the shaft and of the
45 friction wheel 25 and cams 24. Almost immediately the periphery of the friction wheel 25 will engage the roller 21 and continue the rotation of said shaft. As this movement takes place the cams 24 will move into coaction with the roller 21, thereby gripping the paper sheet A thereagainst and starting its movement at right angles and into feeding engagement with the rollers 37-38 and 39. The shaft 23 makes one complete rotation. By that time the stop arm 30 has been

again depressed into the path of the pin 29 and the gripping cams again become inactive. By this time, however, the sheet has been seized by the feeding mechanism of the second machine 8, and is carried off thereby. This operation takes place periodically as succeeding sheets are delivered.

From the foregoing, it is thought that the construction, operation and many advantages of the herein described invention will be apparent to those skilled in the art, without further description, and it will be understood that various changes in the size, shape, proportion and minor details of construction may be resorted to without departing from the spirit or sacrificing any of the advantages of the invention.

Having thus fully described my invention, what I claim as new and desire to secure by Letters Patent, is:-

1. In a sheet moving apparatus, the combination with a moving member, of a rotatable gripping member that coacts therewith, and is rotatable in coaction with the moving member, a stop for holding the gripping member against rotation, and means for intermittently operating the stop to release and permit the rotation of the gripping member in coaction with the moving member.

2. In a sheet moving apparatus, the combination with a moving member, of means for directing sheets to said moving member, a rotatable gripping member having a portion movable into coaction with the moving member to move the sheets directed thereto, means for normally holding the gripping member against rotation with said portion out of coaction with the moving member, and mechanism for periodically effecting the complete rotation of the gripping member to carry said portion into and then again out of coaction with the moving member.

3. In a sheet moving apparatus, the combination with a moving member, of means for directing sheets to said moving member, a rotatable gripping member mounted independently of the moving member and having a portion movable into coaction with the moving member to move the sheets directed thereto, a stop for normally holding the gripping member inactive with said portion out of coaction with the moving member, and means for periodically operating the stop to release the gripping member and permit the complete rotation of the gripping member to carry said portion into and then again out of coaction with the moving member.

4. In a sheet moving apparatus, the combination with a sheet moving member, of means for directing sheets to said moving member, an eccentric gripping device rotatably mounted adjacent thereto and having a portion that moves into and then out

of coaction with the moving member when said device is rotated and when in coaction acting therewith to move a sheet directed to the moving member, and means for normally holding the device inactive and permitting its periodical release and rotation.

5. In a sheet moving apparatus, the combination with a sheet moving member, of means for directing sheets to said moving member, an eccentric gripping device rotatably mounted adjacent thereto and having a portion that moves into and then out of coaction with the moving member when said device is rotated and when in coaction 10 acting therewith to move a sheet directed to the moving member, a rotating means for the gripping device operable by the sheet moving member, and means for normally holding the device inactive and permitting its 15 periodical release and rotation by said rotating means.

6. In a sheet moving apparatus, the combination with a sheet moving member, of means for directing sheets to said moving member, a shaft located adjacent to the sheet moving member, a gripping cam on the shaft, means for normally holding the cam against rotation, and means for effecting the rotation of the cam when released to cause it to move into coaction with the sheet moving member and cause the movement 20 of a sheet directed to the moving member.

7. In sheet moving apparatus, the combination with a sheet moving member, of means for directing sheets to said moving member, a shaft located adjacent to the sheet moving member, a gripping cam on the shaft, means for normally holding the cam against rotation, and a weight for effecting 25 the rotation of the cam when released to cause it to move into coaction with the sheet moving member and cause the movement of a sheet directed to the moving member.

8. In sheet moving apparatus, the combination with a sheet moving member, of a shaft located adjacent to the sheet moving member, gripping cams on the shaft having overbalancing weights that rotate the shaft to cause said cams to rotate into coaction with the sheet moving member, a stop for normally holding the shaft against rotation, and means for periodically actuating 30 the stop to release the shaft.

9. In sheet moving apparatus, the combination with a sheet moving member, of a shaft located adjacent thereto, sheet gripping cams on the shaft rotatable into coaction with the member, a stop for holding the shaft against rotation, means for operating the stop to release the shaft, and means for completely rotating the shaft when released from the stop, including weights that overbalance the cams.

10. In sheet moving apparatus, the combination with a sheet moving member, of a

shaft located adjacent thereto, sheet gripping cams on the shaft rotatable into coaction with the member, a stop for holding the shaft against rotation, a friction actuating wheel for the shaft that bears against 70 the sheet moving means and has a cut-away portion adjacent to the shaft when the latter is held by the stop, means for operating the stop, and means for initiating the movement of the shaft when released from the 75 stop.

11. In sheet moving apparatus, the combination with a sheet moving member, of a shaft located adjacent thereto, sheet gripping cams on the shaft rotatable into coaction with the member, a stop for holding the shaft against rotation, a friction actuating wheel for the shaft that bears against 80 the sheet moving means and has a cut-away portion adjacent to the shaft when the latter is held by the stop, means for operating the stop, and overbalancing weights for initiating the movement of the shaft when released from the stop.

12. In sheet moving apparatus, the combination with a sheet moving roller, of means for delivering sheets with the margins thereof overlying the roller, rotatable cams overlying the roller and having their portions of greater diameter movable into coaction with the roller to grip the sheets thereon, means for holding the cams with their portions of smaller diameter adjacent to the roller during the delivery of a sheet, and means for rotating the cams when a sheet has been delivered to grip it to the roller and effect its movement thereby.

13. In sheet moving apparatus, the combination with a sheet moving roller, of means for delivering sheets in a direction longitudinally of the roller and with the margins thereof overlying the roller, rotatable cams overlying the roller and having their portions of greater diameter movable into coaction with the roller to grip the sheets thereon, means for holding the cams with their portions of smaller diameter adjacent to the roller during the delivery of a sheet, and means for rotating the cams when a sheet has been delivered, to grip it to the roller and effect its movement 100 thereby transversely of the roller.

14. In sheet moving apparatus, the combination with angularly disposed sheet marking apparatus, of means for delivering sheets marked on one apparatus to the other apparatus, said means including a roller disposed longitudinally of the first apparatus, means for feeding the sheets successively longitudinally of said roller and with the margins overlying the same, a shaft journaled over the roller and having cams thereon provided with portions that coact with the roller to grip said margins thereagainst, a stop for holding the shaft against 110 115 120 125 130

movement and with the cams out of co-action with the sheets, means operating with the delivery means to periodically operate the stop, means for moving the shaft when released, and means associated with the roller to carry off the sheets to the second apparatus.

15. In sheet moving apparatus, the combination with angularly disposed sheet marking apparatuses, of means for receiving

the sheets from the first apparatus, including a series of supporting bars upon which sheets slide, a stop for said sheets adjustably slideable along said bars, means for adjusting the stop including an actuating cable 15 member connected to the stop, and wheels at the ends of the bars and around which the cable member passes.

In testimony whereof, I affix my signature.
ALBERT BROADMEYER.
